UNITED STATES PATENT OFFICE.

FRANKLIN P. WHISTLER, OF CADIZ, INDIANA.

PORTABLE FENCE.

SPECIFICATION forming part of Letters Patent No. 300,929, dated June 24, 1884.

Application filed September 19, 1883. (No model.)

To all whom it may concern:

Be it known that I, FRANKLIN P. WHISTLER, a citizen of the United States, residing at Cadiz, in the county of Henry and State of Indiana, have invented a new and useful Improvement 5 in Portable Fences, of which the following is a specification.

My invention relates to the construction of fences so as to be portable and self-supporting by use of ordinary panels of board fence fastened together by loops of wire with cross-brace hooks when the panels are in line, and then bound and held in a self-supporting position by moving said panels so as to form a 15 zigzag line. I obtain these objects in the following way, illustrated in the accompanying drawings, in which—

Figure 1 is a perspective view of two panels of fence in final position, bound together by two loops of wire passing through the loops of a wire cross-brace shaped somewhat like the letter S. Fig. 2 represents two panels of fence in a straight line, fastened together by the loops of wire and cross-brace above named, 20 ready to be moved into position to be self-supporting. Fig. 3 represents a transverse section horizontally across the fence at point of fastening the wire loops around the uprights of panels when standing in line, as in Fig. 2. 25 Fig. 4 is the same as Fig. 3, with the uprights in position occupied by them when the fence is in final position, so as to be self-supporting. Fig. 5 represents the S-shaped brace-hook used between the uprights, and through which 30 the wire loops pass.

Similar letters refer to similar parts throughout the several views.

A B represent two panels of fence. C D represent the uprights at the ends of the panels. E E' represent loops of annealed or other wire. M represents the brace - hook, with loops N N' on the ends thereof, through which the wire loops E E' pass. G represents the middle upright of panel, and H the brace attached to each panel. The panels are made

of boards K K' K" K''' K''', fastened to uprights C D G and brace H, of suitable height and length.

To set the fence up, the panels are placed in line, as shown in Fig. 2, at place desired. The 50 uprights C D are brought as closely together as may be necessary, with brace-hooks M between them, and then the wire loops E E', of good annealed or other suitable wire of suitable size, are passed through the loops N N' 55 on the brace-hook M, and are then bent and twisted around the uprights C D of the two panels having their ends in proximity, between the upper two boards and the lower two boards of the panels, as tightly as can well be 60 done, and according to the requirements of the angle it is desired to give the fence. Then the other ends of the panel are moved into position, so that the two panels shall form any angle desired, sufficient to make the fence self-supporting. Other panels are attached to these, 65 making angles in an opposite direction, so that the fence, when finished, stands in a zigzag position.

I am aware that prior to my invention portable fences have been invented and patented, 70 composed of panels variously fastened together and occupying zigzag and other positions. I do not therefore claim such a combination, broadly.

I am also aware of the patent to C. W. Gates, 75 September 27, 1881, No. 247,493, and of that to J. H. Pearson, April 17, 1883, No. 275,940, and I do not claim anything therein shown or described; but

What I do claim as my invention, and desire to secure by Letters Patent, is—

The combination of the wire loops E E' and the brace-hooks M, having loops N N', with the panels of a portable fence, substantially 80 as and for the purposes set forth.

FRANKLIN P. WHISTLER.
